UNITED STATES PATENT OFFICE

90,441

DESIGN FOR A DERRICK

Charles L. Henry, Pittsburgh, Pa., assignor to
Lee C. Moore & Company, Inc., Pittsburgh, Pa.,
a Corporation of Pennsylvania

Application January 9, 1932. Serial No. 42,438

Term of patent 14 years

To all whom it may concern:

Be it known that I, CHARLES L. HENRY, a citizen of the United States, residing at Pittsburgh, in the county of Allegheny and State of Pennsylvania, have invented a new, original, and ornamental Design for a Derrick, of which the following is a specification, reference being had to the accompanying drawing, forming a part thereof.

Fig. 1 is a side elevation of a four sided derrick or tower, each of the sides being similar to the one shown; and Fig. 2 is a partial view on an enlarged scale showing details of the parts constituting the derrick.

I claim:

The ornamental design for a derrick, as shown and described.

CHARLES L. HENRY.
